UNITED STATES PATENT OFFICE

118,841

DESIGN FOR A FOOD WARMER OR SIMILAR ARTICLE

Carlton G. Towne, Edgewood, Pa., assignor to
The Aluminum Cooking Utensil Company,
New Kensington, Pa., a corporation of Pennsylvania

Application November 17, 1939, Serial No. 88,335

Term of patent 7 years

To all whom it may concern:

Be it known that I, Carlton G. Towne, a citizen of the United States, residing at Edgewood, in the county of Allegheny and State of Pennsylvania, have invented a new, original, and ornamental Design for a Food Warmer or Similar Article, of which the following is a specification, reference being had to the accompanying drawing, forming a part thereof, in which:

Fig. 1 represents a top plan view; and
Fig. 2 represents a perspective view of the food warmer or similar article, showing my design.

I claim:

The ornamental design for a food warmer or similar article, substantially as shown.

CARLTON G. TOWNE.
